UNITED STATES PATENT OFFICE.

HENRY MEHL, OF JERSEY CITY, NEW JERSEY.

DESIGN FOR A BELT-BODY.

SPECIFICATION forming part of Design No. 34,651, dated June 11, 1901.

Application filed May 18, 1901. Serial No. 60,952. Term of patent 3½ years.

To all whom it may concern:

Be it known that I, HENRY MEHL, a citizen of the United States, and a resident of Jersey City, in the county of Hudson and State 5 of New Jersey, have invented and produced a new and original Design for a Belt-Body, of which the following is a specification.

The essential feature of my design consists in a belt-body having a general tapered form 10 in opposite directions from its back, the outer surface being embellished by pronounced ribs spaced apart at the back and gradually converging and finally merging into single broader ribs as they extend toward the opposite ends of the belt-body.

In the accompanying drawings, Figure 1 is a view of the belt-body in elevation. Fig. 2 is a transverse section on the line 2 2 of Fig. 1. Fig. 3 is a transverse section on the line 20 3 3 of Fig. 1, and Fig. 4 is a transverse section on the line 4 4 of Fig. 1.

The portions of the belt-body which gradually taper as they extend in opposite directions from the back are denoted by *a a'*.

The pronounced ribs spaced apart at the 25 back are denoted by *b b'*, and the single ribs into which these ribs *b b'* merge as they extend toward the opposite ends of the belt-body are denoted by *c c'*.

What I claim is—

The design for a belt-body, substantially as herein shown and described.

In testimony that I claim the foregoing as my invention I have signed my name, in presence of two witnesses, this 1st day of May, 35 1901.

HENRY MEHL.
